(57) **CLAIM**

The ornamental design for a kit assembly for adapting gemstone to a ring configuration, as shown and described.

DESCRIPTION

FIG. 1 is an exploded perspective view of a kit assembly for adapting a gemstone to a ring configuration;

FIG. 2 is a perspective view of the ring shank portion of FIG. 1, shown separately to depict aspects of the design that are not visible when combined;

FIG. 3 is a front view of the ring shank portion of FIG. 2; FIG. 4 is a right side view of the ring shank portion of FIG. 2, the left side view being a mirror image thereof;

FIG. 5 is a bottom view of the ring shank portion of FIG. 2; FIG. 6 is a top view of the ring shank portion of FIG. 2; FIG. 7 is a perspective view of the head unit portion of FIG. 1, shown separately to depict aspects of the design that are not visible when combined;

FIG. 8 is a bottom view of the head unit portion of FIG. 7; FIG. 9 is a top view of the head unit portion of FIG. 7; FIG. 10 is a right side view of the head unit portion of FIG. 7, the left side view being a mirror image thereof;

FIG. 11 is a front view of the head unit portion of FIG. 7, the rear view being a mirror image thereof;

FIG. 12 is a perspective view of the screw component portion of FIG. 1, shown separately to depict aspects of the design which are not visible when combined;

FIG. 13 is a side view of the screw component portion of FIG. 12;

FIG. 14 is a top plan view of the screw component portion of FIG. 12;

FIG. 15 is a bottom plan view of the screw component portion of FIG. 12; and,

FIG. 16 is an exploded perspective view of the Kit assembly for adapting gemstone to a ring configuration of FIG. 1. The broken lines in FIG. 8 represent portions of the Kit assembly for adapting gemstone to a ring configuration and form no part of the claimed design. The dot-dot-dash broken lines showing a gemstone in FIGS. 1, 7-11 and 16 represent environmental subject matter only and form no part of the claimed design.

1 Claim, 5 Drawing Sheets
